UNIVERSAL BEVEL

Filed Sept. 17, 1927

UNITED STATES PATENT OFFICE

MALCOLM K. PARKHURST, OF NEW YORK, N. Y., ASSIGNOR TO BROWN & SHARPE MFG.
CO., OF PROVIDENCE, RHODE ISLAND

UNIVERSAL BEVEL

Application filed September 17, 1927. Serial No. 220,112.

This invention relates to universal bevels, and the primary object thereof is to provide a bevel in which the two members are connected for universal movement so as to obtain a very extensive range of adjustments thereby to provide a corresponding range of angles. 5

A further object of the invention is to provide a bevel of this kind in which the connection between the arms or members can be moved to varying positions so as to render same accessible for measurements to be taken.

In the drawings:—

Figure 1 is a top plan view of the invention; 15 Figure 2 is a section on line 2—2 of Figure 1, and

Figure 3 is a view similar to Figure 1 showing the arms in a different adjusted position.

In proceeding in accordance with the present invention two arms 1 and 2 are employed, the arm 1 having one end 3 beveled to 30 degrees, while the arm 2 has its ends 4 and 5 beveled to angles of 45 and 60 degrees respectively. Posts or pillars 6 and 7 are provided 25 with studs 8 on their lower ends which latter are received in perforations provided therefore in the arms and are riveted to the latter. A toggle device composed of links 9 and 10 is provided to connect the members, the outer 30 ends of the arms having openings through which screw studs 11 carried by the posts 6 project. Fastening nuts 12 and 13 are threaded over the studs 11 and hold the links 9 and 10 in adjusted position. The inner ends of 35 the links are provided with registering apertures through which a bolt 14 is passed, the latter having a nut 15 which is employed to hold the links in adjusted position.

By referring to Figure 1 it will be seen 40 that if it is desired to take a reading at the point indicated at A in Figure 1 such reading could not be had were the links 9 and 10 in the dotted line position of Figure 1. However, due to the pivoting of the links to 45 the arms 1 and 2 they can be swung to the full line position of Figure 1, whereby a reading at the point A can be taken.

By referring to Figure 3, it will be seen 50 that the toggle can be manipulated so as to bring the arms in a different relation. It

should be understood in this regard that the above instances of the relationship of the arms as shown in the drawings, are given as examples and not exhaustive enumeration of all possible angles or combinations which can 55 be had by use of the present invention.

It will further be noted that the device is simple and positive and eliminates the presence of all slots. The toggle device is pivoted at a relatively fixed point to each of the arms 60 of the bevel, so that the adjustments can be made easily and quickly by merely moving the posts about the three pivots which the present invention embodies.

Having thus described my invention what 65 I claim as new and desire to secure by Letters Patent is:—

1. In a bevel, a pair of elongated members having beveled ends, a post secured at one 70 end to each of said members respectively adjacent the ends thereof, a reversible toggle device composed of a pair of links, means to pivotally connect one end of each link to the free ends of the respective posts, and means to pivotally connect the opposite ends of the 75 links together, said last named means being movable to lie on opposite sides of a line drawn between the first named means which pivotally connect the links to said members and said posts being of a length to enable a 80 clear vision of the angular relation of the members to be had beneath the toggle device.

2. In a bevel, a pair of elongated members having beveled ends, a reversible toggle device composed of a pair of links, means to 85 pivotally connect one end of each link to each of said members respectively adjacent the ends thereof, and means to pivotally connect the opposite ends of the links together and to hold same in adjusted positions, said last named means being movable to lie on opposite sides of a line drawn between the said means which pivotally connect the links to the said members and the members being capable of being swung past said means which connects the links together. 90

In testimony whereof I have signed my name to this specification.

MALCOLM K. PARKHURST.
